UNITED STATES PATENT OFFICE.

FRANK A. JAHN, OF DAVENPORT, IOWA.

EXPLOSIVE-ENGINE.

No. 831,283.

Specification of Letters Patent.

Patented Sept. 18, 1906.

Application filed August 12, 1905. Serial No. 273,892.

To all whom it may concern:

Be it known that I, FRANK A. JAHN, a citizen of the United States, residing at Davenport, in the county of Scott and State of Iowa, have invented new and useful Improvements in Explosive-Engines, of which the following is a specification.

My invention relates to explosive-engines, and more particularly to the means for operating the exhaust-valve.

The object of the invention is to provide means for a rapid opening and closing of the valve.

A further object is to provide a valve-gear, which shall be simple and efficient in operation, having no complicated parts.

These objects are attained by certain novel features of construction hereinafter described and claimed.

In the accompanying drawings, Figure 1 is a side elevation of an explosive-engine provided with my valve-gear. Figs. 2 to 6 are diagrams illustrating the operation of the gear.

Referring specifically to the drawings, 10 denotes the engine-frame; 11, the cylinder; 12, the piston-rod connected to the crank-shaft 13, which is journaled in bearings on the frame 10.

At 14 is indicated a lever which is fulcrumed, as at 15, on the engine-frame. One end of the lever is connected to the exhaust-valve stem 16, and its opposite end carries a pin 17, on which a star-wheel 18 is rotatably mounted. The star-wheel has four arms 19, the outer ends of which are recessed, as at 20, for a purpose to be hereinafter described.

At 21 is indicated a collar which is fast on the crank-shaft. This collar carries a pin 22, which extends into the path of the arms 19 of the star-wheel and cooperates therewith to operate the exhaust-valve in a manner to be hereinafter described.

The end of the lever 14, carrying the star-wheel, is normally lifted by a spring 23, which is fastened to a suitable bracket 24 on the engine-frame.

In Figs. 2 to 6 the operation of the mech-

anism is clearly shown. Fig. 2 shows the position of the parts at the beginning of the suction-stroke. Fig. 3 shows the end of the suction-stroke. During these two strokes the star-wheel is idle, not being engaged by the pin. During the compression-stroke the pin strikes one of the arms 19 and tilts the star-wheel so that one of its arms is extended directly into the path of the pin 22, as shown in Fig. 4, which is the end of the compression-stroke. The charge is now fired, and at the end of the power-stroke the pin reaches the arm, as shown in Fig. 5, so that during the exhaust-stroke the pin engages the recess 20 in the arm, as shown in Fig. 6, and bears down thereon, whereby the lever 14 is tilted, which opens the exhaust-valve. When the pin leaves the arm, the lever is pulled up by the spring 23, which closes the exhaust-valve and brings the star-wheel to its normal position, as shown in Fig. 2, ready for the next cycle. The star-wheel works tightly, so that it will not spin or turn beyond position.

Having thus described my invention, what is claimed as new, and desired to be secured by Letters Patent, is—

1. The combination with a crank-shaft 75 and the exhaust-valve of an explosive-engine, of a lever for operating the valve and carrying a rotatable star-wheel, and means carried by the crank-shaft for setting the star-wheel and bearing down thereon to tilt the lever and open the exhaust-valve.

2. The combination with a crank-shaft and the exhaust-valve of an explosive-engine, of a lever for operating the valve, a rotatable member carried by the lever and having radial arms, and a trip carried by the crank-shaft and arranged to bear on the outer ends of the arms to tilt the lever and open the exhaust-valve.

In testimony whereof I have signed my name to this specification in the presence of two subscribing witnesses:

FRANK A. JAHN.
